RHEOSTAT

Masami Takanashi, Tokyo, Japan, assignor of
one-half to Shungo Furui, Yokohama, JapanApplication April 10, 1935, Serial No. 15,642
In Japan June 12, 1934

4 Claims. (Cl. 201—60)

This invention relates to improvements in rheostats, more particularly to rheostats of sliding contact type, for use in the volume control in electrical phonographs, radio broadcasting receivers or the like.

5 The resistance of resistance wire in general varies linearly with its length. For this reason, the volume control in an electrical phonograph or a radio broadcasting receiver cannot be effected in an efficient manner by means of an ordinary 10 rheostat.

15 The volume control can be accomplished theoretically in a desired manner by suitably varying the diameter of the wire along the length thereof. This, however, requires a complicate process in its manufacture and consequently is expensive. Such means, moreover, do not give very satisfactory results from practical point of view.

20 It is accordingly an object of the present invention to obviate the aforesaid disadvantages of the rheostats known heretofore and to provide a rheostat by means of which the volume of reproduced sounds can be controlled in a manner proportionate with the movement of controlling means.

25 It is a further object of the invention to provide a rheostat of the sort just mentioned in a cheap and economical manner.

According to my invention, any desired resistance characteristics, in which the effective resistance, instead of linearly with its length, varies 30 according to any desired curve, can be obtained by coating a portion or whole of each turn of the coil making up a rheostat with material of a higher electric conductivity. In other words, 35 by making the boundary line formed by the edges of coated portions of the turns of coil to extend along a straight line or in accordance with a suitable curve, the effective resistance, or the resistance from one terminal to a contactor brush, can 40 be made to vary parabolically, exponentially or in any predetermined manner with respect to the position of the brush. By this means, it is made possible to control the volume of reproduced sound in such a manner that it is substantially 45 proportional to the displacement of the contactor brush.

In the accompanying drawing:

Fig. 1 shows an end view, as cover removed, of 50 a rheostat assembly according to my invention.

Fig. 2 shows a central cross sectional view thereof taken at the line II—II of Fig. 1, with the cover on.

Fig. 3 shows a plan view of a part of the rheostat proper, as it is developed in a plane.

Fig. 4 is a plan view of a modified form of the invention, corresponding to Fig. 3.

Referring to Figs. 1 to 3, and more particularly to Figs. 1 and 2, 1 is a casing in which are housed a rheostat proper and accessories thereof. The casing 1 has rigidly mounted thereon a sleeve 2, through the inner bore of which extends a controlling shaft 3. The sleeve 2 has screw-threads 4 and is adapted with the cooperation of nut 5, to serve as a support for mounting the rheostat on 10 a suitable panel. At the inner surface of the cylindrical peripheral portion of the casing 1 is provided a lining 6 of a suitable insulating material for protecting the rheostat proper from coming into contact with the wall of the casing 1. 15 The rheostat proper which is designated by numeral 7 is composed of an insulating inner core 8, resistance wire 9 wound on the core and terminals 10 connected to the ends of the resistance wire. The rheostat proper is so disposed within the casing 1 that it is prevented from coming into contact with the wall of the casing by means of the lining 6 and the terminals 10 are caused to project outwardly from the apertures provided at the peripheral wall of the casing and fixed to the casing in known manner. At the upper edge 20 portion of the rheostat proper a sliding contactor 11 is provided to contact resiliently with it. The contactor 11 is formed as an extension of a metallic disc 12 having an arcuate aperture 13 to render the disc resilient. The metallic disc 12 is 25 mechanically fixed to the controlling shaft 3, but insulated electrically therefrom in known manner. Another terminal 14 is provided on the casing 1, as insulated therefrom. This terminal 30 14 is connected to a metallic member 15, which is adapted to be in sliding contact with the disc 12, the terminal 14 being in this manner in electrical connection with the contactor 11. The hub portion of the member 15 is electrically insulated 35 from the shaft 3 by means of the central insulating member 16. The shaft 3 is formed with an annular groove 17 for receiving therein a wedge member 18 for preventing the longitudinal displacement along the shaft of the assembly including the sleeve 2 and the casing 1. The casing 1 is covered by a cover member 19. The casing 1, in cooperation with the cover 19, serves also as 40 electrostatic shield.

The above mentioned construction is known 50 in itself. The main feature of invention will now be described in detail.

Referring to Fig. 3 in particular, which illustrates one realization of my invention, the resistance wire 9, such as Manganin, Nichrome and 55

Advance, is wound on the core of insulator 8 in such a manner that adjacent turns do not come into contact with each other. 20 indicates portions of turns of wire which are coated, electrolytically for example, with material of a higher electric conductivity, such as copper or silver. In this connection, I have found that the electrolytical coating can be advantageously carried out by first coating the wire preliminarily with nickel 10 and then with copper or silver. Adjacent turns of the coated portions too are so arranged that they do not come into contact with each other.

The coating of the turns of the wire is carried out in such a manner that the contour line 21 of 15 the edges of coated portions form substantially a straight line, when developed, extending diagonally from one side to the other side of the coil. The coating portions 20, however, can be so prepared as to make the contour line 21 to extend 20 from one side to the other side of the coil according to any desired curve, for example according to an exponential curve, as shown in Fig. 4.

The core of insulator 8 need not necessarily be 25 in plate form, but it may be made cylindrical or oval in cross-section, or any other suitable form.

In case a rheostat according to the invention 30 is intended to be utilized for the purpose of controlling the volume of reproduced sounds in an electrical phonograph or a radio broadcasting receiver, it can be treated under suitable heat and pressure in a mold with molding powder, such as bakelite or ebonite, so as to form around it an external protective covering.

The invention is particularly useful, in its application, as rheostats for controlling the volume 35 of sound in electrical phonographs or radio broadcasting receivers, as has been indicated hereinbefore, although it is also useful in general current regulating purposes, inasmuch as its characteristic curve can be varied at will by suitably forming the conductive coating on the rheostatic coiled wiring. Moreover, its manufacture is very easy 40 and inexpensive owing to the fact that it can be produced by a mere coating of ordinary rheostat 45 by a material of good electrical conductivity.

What I claim is:

1. A rheostat for controlling the volume of reproduced sound, comprising a coil of resistance wire, the turns of which are spaced apart out of contact with each other, and a coating on a portion of the turns of said coil of metal having higher electrical conductivity than said wire, said coating consisting of an electrolytic deposit of nickel on the wire and an electrolytic deposit of copper on the nickel. 10

2. A rheostat for controlling the volume of reproduced sound, comprising a coil of resistance wire, the turns of which are spaced apart out of contact with each other, and a coating on a portion of the turns of said coil of metal having 15 higher electrical conductivity than said wire, said coating consisting of an electrolytic deposit of nickel on the wire and an electrolytic deposit of silver on the nickel.

3. A rheostat for controlling the volume of reproduced sound, comprising a coil of resistance wire, the turns of which are spaced apart out of contact with each other, and a coating of metal of higher conductivity than said wire on said coil, said coating consisting of a deposit of nickel 25 on said wire and a deposit of metal of higher conductivity than nickel on said nickel deposit, the contour line connecting the boundary of said coated portion of each turn of wire extending from one end of the coil to the other substantially 30 according to an exponential curve.

4. A rheostat for controlling the volume of reproduced sound, comprising a coil of resistance wire, the turns of which are spaced apart out of contact with each other, and a coating of metal 35 of higher conductivity than said wire on said coil, said coating consisting of a deposit of nickel on said wire and a deposit of metal of higher conductivity than nickel on said nickel deposit, the contour line connecting the boundary of said coated 40 portion of each turn of wire extending from one end of the coil to the other substantially according to a parabolic curve.

MASAMI TAKANASHI. 45
